UNITED STATES PATENT OFFICE.

HERMAN ABRAMS, OF PHILADELPHIA, PENNSYLVANIA.

DESIGN FOR A WALL-BRACKET LIGHTING FIXTURE.

Application filed December 27, 1921. Serial No. 525,257. Term of patent 3½ years.

To all whom it may concern:

Be it known that I, HERMAN ABRAMS, a citizen of the United States, residing at Philadelphia, in the county of Philadelphia and State of Pennsylvania, have invented a new, original, and ornamental Design for a Wall-Bracket Lighting Fixture, of which the following is a specification, ref-

erence being had to the accompanying drawing, forming a part thereof.

The drawing is a front elevation of the wall bracket lighting fixture.

I claim:

The ornamental design for a wall bracket lighting fixture as shown.

HERMAN ABRAMS.
